DESIGN FOR A VISIBLE COIN SLOT ATTACHMENT FOR COIN CONTROLLED DEVICES

Francisco A. Toce, Sr., Houston, Tex.

Application June 8, 1936, Serial No. 63,107

Term of patent 3½ years

To all whom it may concern:

Be it known that I, Francisco A. Toce, Sr., a citizen of the United States, residing at Houston, in the county of Harris and State of Texas, have invented a new, original, and ornamental Design for a Visible Coin Slot Attachment for Coin Controlled Devices, of which the following is a specification, reference being had to the accompanying drawing, forming part thereof.

Figure 1 is an elevational view partly in per-

spective of a visible coin slot attachment, showing my new design.

Figure 2 is a view of the same taken in perspective.

I claim:

The ornamental design for a visible coin slot attachment for coin controlled devices, substantially as shown.

FRANCISCO A. TOCE, SR.
